UNITED STATES PATENT OFFICE.

RICHARD TITUS AND DOR C. COVERT, OF BOWLING GREEN, OHIO,
ASSIGNORS OF THREE-FOURTHS TO STEPHEN FLOYD AIKEN AND
ALEXANDER C. McDONALD.

STUFFING-BOX.

SPECIFICATION forming part of Letters Patent No. 679,922, dated August 6, 1901.

Application filed March 5, 1901. Serial No. 49,873. (No model.)

To all whom it may concern:

Be it known that we, RICHARD TITUS and DOR C. COVERT, citizens of the United States, residing at Bowling Green, in the county of 5 Wood and State of Ohio, have invented a new and useful Stuffing-Box, of which the following is a specification.

Our invention is an improved stuffing-box for the polish-rod of an oil-well; and it consists in the peculiar construction and combination of devices hereinafter fully set forth and claimed.

The object of our invention is to provide an improved stuffing-box which is adapted to 15 permit the lateral play of the polish-rod incident to the operation of the walking-beam or pumping-jack, which operates the polish-rod, and to effectually pack the latter, a further object of our invention being to provide 20 means to maintain the requisite pressure on the packing-rings in the stuffing-box and to regulate the pressure thereon.

In the accompanying drawings, Figure 1 is a vertical sectional view of a stuffing-box embodying our improvements, showing the same in operative relation to a polish-rod. Fig. 2 25 is a detail view of one of the adjusting-nuts.

The stuffing-box 1 is cylindrical in form, has the bore 2 in its upper portion, and is provided on its lower side with an exteriorly-threaded portion 3 of reduced diameter, which is adapted to be screwed into the upper end of an oil-well tubing. The bore 4 of the said threaded extension 3 is of greater diameter 35 than the polish-rod *a*, which operates therein, excepting at its upper portion, where the said bore is contracted, as at 5, and engages the polish-rod. The said contracted portion of the bore serves to scrape the paraffin from 40 the polish-rod and also serves to center the latter in the stuffing-box and at the same time permits the polish-rod to play laterally in the stuffing-box, this lateral motion, as is well known, being imparted to the polish-rod 45 by the walking-beam or pumping-jack.

In the bottom of the bore 2 is disposed a bushing 6, which is preferably made of brass and has its upper side concaved, as shown. The packing 7, which is preferably hemp or

rubber rings, is placed in the stuffing-box 50 1 and bears on the bushing 6. A gland 8 fits and operates in the stuffing-box 1, bears upon the packing and serves to compress the same in the stuffing-box and fit the packing snugly around the polish-rod. The bore in the upper portion of the follower is enlarged, as at 9, and the lower portion thereof is contracted, as at 10, hence serving to center the polish-rod, while admitting of the lateral play thereof. The under side of the gland is concaved, 55 as shown, the opposing concaved faces of the gland and bushing serving to compress the outer sides of the packing-rings, and hence expand the latter on their inner sides, which contact with the polish-rod. 60

The stuffing-box is provided at its upper end on opposite sides with lugs 11, in which are vertical guide-openings 12. The gland 8 is provided at its upper end on opposite sides with lugs 13. Adjusting-bolts 14 are 70 secured in the lugs 13 and depend therefrom, the angular heads 15 of said bolts being countersunk in similar-shaped recesses on the upper sides of the lugs. Said bolts pass through the guide-openings 12 in the lugs of the stuffing-box, and on the lower portions of the said bolts are coiled compression-springs 17, the tension of which may be varied at will by nuts 18, which are adapted to be turned by hand. It will be understood that the springs 80 and bolts coöperate to press the gland downwardly in the stuffing-box, and thereby exert the requisite compression on the packing-rings. This compression may be varied as may be required by means of the nuts 18. 85

When the bushing 6 becomes worn, it may be readily removed and another substituted in its stead. The bushing sustains all the wear, and as the same is removable and may be renewed the stuffing-box is exceedingly 90 durable.

Having thus described our invention, we claim—

A stuffing-box for the polish-rod of an oil-well, having an extension at its lower end to 95 couple said stuffing-box to an oil-well tubing, the bore of said extension being of greater diameter than the polish-rod and being con-

tracted at its upper end to engage the polish-rod, said stuffing-box having guide-lugs projecting therefrom, a removable bushing in said stuffing-box, a follower movable in said 5 stuffing-box, having a bore of greater diameter than the polish-rod and contracted at its lower end to engage the polish-rod, said gland being further provided with lugs projecting therefrom, adjusting-bolts attached 10 to the lugs of the gland and guided by the guide-lugs of the stuffing-box, compression-springs on said bolts, bearing under the lugs of the stuffing-box, and adjusting-nuts on the

said bolts, engaging the lower ends of said springs and adapted to vary the tension there- 15 of, for the purpose set forth, substantially as described.

In testimony that we claim the foregoing as our own we have hereto affixed our signatures in the presence of two witnesses.

RICHARD TITUS.
DOR C. COVERT.
